UNITED STATES PATENT OFFICE
2,573,545
LADY'S GARMENT CONSTRUCTION
Theodore I. Cooper, Detroit, Mich.
Application February 23, 1950, Serial No. 145,867
4 Claims. (Cl. 2—105)

1
This invention relates to a lady's garment construction, and more particularly to a novel pattern which may be used in the making of a lady's dress, blouse, lingerie, suits, housecoats, negligees and other similar garments.

It is the object of the present invention to provide a novel pattern for a lady's blouse, for example, which is so cut, and which is so formed, that when certain portions thereof are sewed together there will be formed within the completed garment a transversely extending form delineating portion, of substantially conical shape.

It is the further object of this invention to provide a novel pattern for a lady's garment which is simple in construction and which, when properly employed may be used to construct a lady's garment having outwardly projecting form delineating portions, as an integral part thereof.

These and other objects will be seen from the following specification and claims in conjunction with the appended drawing, in which:

Fig. 1 is a front elevational view of a pair of oppositely arranged pattern elements for a portion of a lady's garment embodying the present invention.

Fig. 2 is a front elevational view of the front portion of a lady's garment when the pattern elements shown in Figure one are arranged and sewed together as indicated; and

Fig. 3 is a section taken on line 3—3 of Fig. 2.

It will be understood that the above drawing illustrates merely a preferred embodiment of the invention and that other embodiments are contemplated within the scope of the claims hereinafter set out.

Referring to the drawing, one of the pattern elements shown in Fig. 1 includes the base element 11, with neck portion 12, shoulder portion 13, sleeve portion 14, waist portion 15, bottom portion 16, and the rectangular portion 17 which is adapted to be folded under along the line 18 when joined to the elongated flap 20, along the dotted line 21.

The base element 11 has extending therefrom as an integral part thereof the downwardly and angularly inclined flap 20 with outer peripheral edge 26, which terminates at its upper end at the neck portion 12.

The base element 11 is formed with a substantially triangular notch 19 which includes the sides 22, 23 and 24, the latter being an extension at the upper end of the flap 20.

There is also formed within said base element substantially below said notch the similarly shaped triangular tab 21 with sides 22 and 25,

and said pattern being cut away at 28, defining thereunder the rectangular portion 17 which is adapted for folding under said base element along the line 18.

2
said pattern being cut away at 28, defining thereunder the rectangular portion 17 which is adapted for folding under said base element along the line 18.

5 The pattern including the base element 11 is then rearranged as shown in Fig. 2 with the flap 20 being swung downwardly so that its inner longitudinal edge 21 is joined to the lower portion of base element 11 along the line 18—21.

10 Furthermore the apex formed by the intersecting sides 23 and 24 of said triangular notch 19 is projected over the apex of the triangularly shaped tab 21, so that the edges 22 and 23 are arranged in alignment, and the edges 24 and 25 are arranged in alignment, after which said aligned edges are stitched together to produce the form of garment shown in Fig. 2.

By this arrangement the line 21 of the pattern is stitched along the line 18 so that now 20 the line 26 of the pattern will be substantially vertical as shown in Fig. 2.

As indicated in Fig. 3 when the garment construction has been so assembled and secured together as by a plurality of stitches there will be 25 provided in the central portion of each base element a transverse outwardly projecting form delineating portion of substantially conical shape.

It is quite apparent that while in the preferred embodiment shown in the drawing a blouse is 30 constructed from said pattern, it is contemplated that this same or similar pattern may be employed to make ladies' dresses, lingerie, suits, housecoats, negligees and other articles of feminine apparel.

35 The provision of the triangular notch 19 within the pattern and the corresponding triangular tab therebelow, and the superimposing of said notch over and upon said tab, when properly stitched together, will produce the transverse outwardly projecting form delineating elements 40 which are shown in Figures 2 and 3.

Having described my invention, reference should now be had to the claims which follow for determining the scope thereof.

45 I claim:

1. In a lady's blouse, a base element including neck, shoulder, sleeve and waist boundaries, an elongated flap extending angularly downward from the upper inner portion of said base, the latter having a substantially triangular notch in the central portion thereof, a similarly shaped tab formed in said base below said notch, said flap being projected downwardly to a vertical position into alignment with the lower upright 55 edge of said base and with said notch arranged

over said tab, and stitches inter-connecting the corresponding adjacent sides of said notch and tab and said flap and upright edge, whereby a central portion of said base projects transversely therefrom in a form-delineating substantial conical shape.

2. In a pattern for a lady's garment, a substantially flat base element, an elongated flap extending angularly downward from the upper inner portion of said base, the latter having formed in the central portion thereof, a substantially triangular notch, and a similarly shaped tab, formed in said base, below said notch, the lower portion of said base having an inner upright edge, said flap when projected downwardly to a substantially vertical position being cooperable with said upright edge, the respective adjacent edges of said slot and tab being cooperable to define a central outwardly projecting form delineating garment portion of substantially conical shape.

3. In a pattern for a lady's blouse, a base element including neck, shoulder, sleeve and waist boundaries, an elongated rectangularly shaped flap extending angularly downward and outwardly from an upper inner portion of said base, the latter having a substantially triangular notch in the central portion thereof, with a portion of said flap forming one boundary of said notch, and

a similarly shaped substantially triangular tab formed in said base below said notch, the lower portion of said base having an inner upright edge, the inner edge of said flap being cooperable with said upright edge and the respective adjacent edges of said notch and tab being cooperable.

4. In a pattern for a lady's garment, a substantially flat base element, an elongated rectangularly shaped flap extending angularly downward and outwardly from the upper inner portion of said base, the latter having formed in the central portion thereof a substantially triangular notch, with a portion of said flap forming one boundary of said notch, and a similarly shaped substantially triangular tab formed in said base below said notch, the lower portion of said base having an inner upright edge, the inner edge of said flap being cooperable with said upright edge and the respective adjacent edges of said notch and tab being cooperable.

THEODORE I. COOPER.
